UNITED STATES PATENT OFFICE.

JOHN F. WRIDE, OF BROOKLYN, NEW YORK, ASSIGNOR OF ONE-HALF TO
OLIVER R. BONNER, OF BROOKLYN, NEW YORK.

SOCKET-COVER AND GLOBE-HOLDER.

SPECIFICATION forming part of Letters Patent No. 703,880, dated July 1, 1902.

Application filed September 20, 1901. Serial No. 75,686. (No model.)

To all whom it may concern:

Be it known that I, JOHN F. WRIDE, a citizen of the United States, and a resident of the city of New York, borough of Brooklyn, in the county of Kings and State of New York, have invented a new and Improved Socket-Cover and Globe-Holder, of which the following is a full, clear, and exact description.

The invention relates to electric-lamp fixtures; and its object is to provide a new and improved fixture which is simple and durable in construction and arranged to combine a socket-cover and globe-holder which can be readily and securely placed in position to cover the lamp-socket and to form an exceedingly strong globe-holder requiring no separate attachment on the cover.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a side elevation of the improvement as applied. Fig. 2 is a plan view of the same with the lamp or bulb removed, and Fig. 3 is a sectional side elevation of the improvement.

The improved socket-cover and globe-holder is formed from a single piece of metal or other suitable material spun or otherwise formed into the desired shape, so that the globe-holder forms an integral part of the socket-cover. The fixture, as shown in Fig. 3, consists of the cylindrical portion A, from the upper end of which flares outwardly the neck A', terminating in the rim A², adapted to receive and hold the globe. Portions of the neck A' are cut and bent inwardly to form extensions A³ for the cylindrical portion A to engage with the latter the socket B of the electric lamp. The socket B is of any approved construction and is adapted to support the bulb C, as indicated in Fig. 1; but it is expressly understood that the cylindrical portion A and its extensions A³ fit snugly onto the exterior surface of the said socket.

The lower end of the cylindrical portion A

fits into and is secured to the cap D, held on the upper end of the socket-support E, and a suitable fastening means may be employed to fasten the said cylindrical portion A and the cap together. For instance, as shown in the drawings, the cylindrical portion A is formed with a bayonet-slot A⁴, engaging a pin F, carried by the dome-shaped cap D. The rim A² is provided with suitable fastening means, such as screws G, for securely locking the globe in position on the rim A² of the globe-holder. The cylindrical portion A may also be provided with a cut-out portion A⁵ (see Fig. 1) for the passage of the shank 65 of the key H, used for operating the contact mechanism in the socket B.

It is evident that by forming the socket-cover integral with the globe-holder it requires but a simple attachment of the device 70 on the socket B, and a separate adjustment and securing of the globe-holder on the socket-cover is not necessary. Furthermore, by forming the two devices of one piece of material it is evident that a very strong and 75 durable fixture is provided to securely hold the globe in position on the lamp.

Having thus described my invention, I claim as new and desire to secure by Letters Patent—

1. As an article of manufacture an electric-light fixture comprising a cap adapted to serve as a support and provided with a screw, a socket-cover provided with a bayonet-slot for engaging said screw, said socket-cover being 85 provided with a cylindrical portion and with a ring integrally connected with said cylindrical portion by a flaring neck, portions of said neck being cut and formed into a substantially cylindrical portion, the same forming an extension of said first-named cylindrical portion and located within said ring and concentric thereto, and a socket located partly within said cylindrical portion and partly within said cylindrical extension thereof. 95

2. An electric-lamp fixture comprising a combined socket-cover and globe-holder having a cylindrical portion to fit over the socket and a flaring portion connecting said cylindrical portion with the globe-holder and having portions of the flaring portion separated at their upper ends and at their sides and

bent inwardly at their free ends to approximately coincide with the cylindrical portion which fits over the socket whereby to form a prolongation of said cylindrical portion toward the outer end of the fixture substantially as and for the purposes set forth.

In testimony whereof I have signed my

name to this specification in the presence of two witnesses.

JOHN F. WRIDE.
